REFRIGERATING APPARATUS

Harry F. Smith, Dayton, Ohio, assignor to General
Motors Corporation, Dayton, Ohio, a corpora-
tion of Delaware

Application December 21, 1936, Serial No. 116,944

2 Claims. (Cl. 257—263)

This invention relates to heat transfer devices and particularly to condenser constructions for refrigerating systems.

An object of my invention is to provide a heat exchanger of the type having a closed fluid conveying passage extending therethrough and which exchanger is of improved construction and increased efficiency.

Another object of my invention is to provide a heat exchanger comprising a plurality of parts adapted to be assembled together and bonded to one another by present-day economical copper hydrogen brazing methods to form a unitary device of improved structural strength.

15 A further object of my invention is to provide an improved heat exchanger structure having separate heat transfer fins disposed between and contacting closed fluid conveying ducts thereof and having the fins interlocking and contacting one another to provide a continuous fin surface extending entirely across portions of the structure to reduce the temperature gradient between certain portions of the heat exchanger.

20 A still further object of my invention is to increase the heat transfer efficiency of a heat exchanger to thereby obtain greater capacity from an exchanger of given size or to decrease the overall dimensions of an exchanger of a predetermined capacity.

25 In carrying out the foregoing objects it is a still further and more specific object of the invention to form certain portions of the fluid conveying conduits of my improved heat exchanger from strips of sheet metal that are bent or folded into the desired shape and have certain portions thereof secured together to provide parts of the fluid conduits with a plurality of closed passages.

30 Further objects and advantages of the present invention will be apparent from the following description, reference being had to the accompanying drawings, wherein a preferred form of the present invention is clearly shown.

In the drawings:

Fig. 1 is a front elevational view of a heat exchanger constructed in accordance with my invention;

Fig. 2 is an enlarged fragmentary end view of the heat exchanger taken in the direction of the arrow 2 in Fig. 1 and showing the end portion partly in elevation and partly in section;

Fig. 3 is a fragmentary view of the heat exchanger partly in elevation and partly in section and taken on the line 3—3 of Fig. 2;

Fig. 4 is a fragmentary horizontal view of the heat exchanger taken on the line 4—4 of Fig. 2;

Fig. 5 is a fragmentary sectional view similar to Fig. 4 and taken on the line 5—5 of Fig. 6 showing a modified end construction of the heat exchanger;

Fig. 6 is a fragmentary sectional view of the modified end construction of the heat exchanger taken on the line 6—6 of Fig. 5;

Fig. 7 is a plan view of a metal strip adapted to be stamped and formed to provide a fin element for the heat exchanger;

Fig. 8 is a sectional view taken on the line 8—8 of Fig. 7 through the metal strip after having apertures stamped therein; and

Fig. 9 is a fragmentary sectional view through a fin element formed from the metal strip disclosed in Fig. 8 in accordance with the invention.

Referring to the drawings, for illustrating my invention, I have shown in Fig. 1 thereof a unitary heat exchanger generally represented by the reference character 10, such for example as a condenser for the refrigerating system. The heat exchanger 10 comprises a plurality of superimposed and horizontally extending parallelly arranged closed refrigerant conveying conduits 11. The conduits 11 extend beyond the exchanger proper and have pressed sheet metal cap members 12 secured to the ends thereof. A plurality of pipes or conduits 13 secured to certain of the cap members 12 connect the refrigerant conveying conduits 11 in communicative relation to provide a series flow for refrigerating fluid through the condenser or exchanger 10.

The condenser 10 may be provided with inlet and outlet pipe connections 14 and 15 respectively at one end thereof. The heat exchanger 10 also comprises a fin arrangement for augmenting the transfer of heat from fluid in conduits 11 to the air or other cooling medium for the fluid and this arrangement includes a plurality of fins 16. A metal plate 17 is secured to the fins 16 at the top and bottom of the exchanger 10 and these plates have flanges 18 extending outwardly therefrom which serve as mounting means for the exchanger or for connecting same in an enclosed path of air such as to a shroud or the like in which is mounted an air circulating fan or blower.

Referring now to Fig. 2 of the drawings it will be noted that the fluid conduits 11 extending through the heat exchanger 10 are flattened as at 21 to provide a relatively flat elongated passage for the flow of refrigerant therein. After the tubes or conduits 11 have been flattened

as at 21 a strip of metal 22 corrugated as at 23 is inserted in each of the conduits. The corruga-

tions 23 formed in metal strip 22 provide flat portions 24 which lie against or abut the walls of conduit 11. Metal strip 22 thus serves to divide the refrigerating fluid flowing through conduit 11 into a plurality of paths of flow to thereby augment the transfer of heat between the fluid and the conduit walls and consequently to the fin arrangement 16 of the heat exchanger. The cap members 12 of conduits 11 have an elongated portion 25 which is flattened to correspond to the flattened conduits 11 and this portion 25 fits over and is secured to the ends 26 of the conduits 11 (see Figs. 3 and 4). The ends of the elongated portions 25 of cap members 12 are flared outwardly as at 27 adjacent the exchanger 10 and these flanges are secured to the end portions of the fin arrangement 16.

The fin arrangement 16 of the heat exchanger disclosed comprises a plurality of corrugated or folded metal strips generally represented by the reference character 31. There is a corrugated strip 31 interposed between each of the superimposed conduits 11 and it will be noted that each corrugated strip provides a plurality of relatively tall thin passages through the exchanger 10 for the flow of air or other cooling fluid therethrough. The blank strip of metal from which a corrugated fin element 31 is formed is disclosed at 32 in Fig. 7. The blank 32 is first punched out as 33 to provide a plurality of spaced apart elongated apertures or openings. The material adjacent the lengthwise opposed walls 34 of the openings formed by the punched out portions 33 are then bent in opposite directions to one another as shown at 35 and 36 in Fig. 7 to provide legs or flanges extending at right angles to the extension of the strip 32. Alternate apertures in the blank strip 32 have the opposed walls thereof bent in opposite directions to the walls of adjacent apertures as disclosed in Fig. 8 of the drawings for a purpose to be presently described. The punched and preformed thin metal strip 32 shown in Fig. 8 is then folded or bent on lines passing through the center of an extending parallel 45 with the extension of each aperture formed in strip 32 to produce a length of corrugated strip form 31, a fragmentary portion of which is shown in Fig. 9 of the drawings. By referring to Fig. 9 it will be seen that the folding operation performed on the preformed flat strip 32 causes the strip to assume a zig-zag form with the legs or flanges 35 and 36 thereof extending in the same direction and disposed closely adjacent one another. It will also be observed that the material 50 between the ends of the apertures in blank 32 and the lengthwise edges of the blank extend beyond the end walls of the apertures as at 37 to provide the corrugated structure 31 with raised portions on each side of a flat substantially continuous surface formed by the legs or flanges 35 and 36. The flat substantially continuous surfaces formed by the legs 35 and 36 inwardly of the extensions 37 are adapted to be placed in abutting relation with and secured to the flattened surface 21 of conduits 11.

In assembling the parts of the exchanger described a corrugated fin strip element 31 is placed upon a plate 17 and a conduit 11 is then placed upon the fin element 31 with the flattened wall 21 thereof in intimate contact with the substantially continuous flat surface of the fin formed by the legs 35 and 36. Another fin element or structure 31 is then placed over the conduit 11 and the superimposing operations described are continued until a heat exchanger of a predeter-

mined size is assembled. The cap members 12 with the conduits 11 secured thereto are then assembled upon the heat exchanger with the ends 26 of conduits 11 fitting into the elongated portion 25 of cap members 12 and the outwardly flared parts 27 in abutting relation with the end of the fin elements 31 employed to provide the fin arrangement for the structure. It will be noted that, during the superimposing assembly operation of the parts, the extending portions 37 of the fin elements 31 overlap or straddle the conduits 11. This straddling of fin members or elements 31 on conduits 11 is an essential feature of this invention in order to permit the substantially continuous flat portions formed by legs 15 35 and 36 to abut against the flattened portions 21 of the conduits. The extending portions 37 on fin members 31 are of sufficient length to interfere with the extending portions 37 on other superimposed fin members 31 during the assembly 20 operation. The extending portions 37 of members 31 which straddle the conduits 11 are therefore telescoped together so as to be disposed in contacting relation as shown in Fig. 3. The smooth rounded end portions of the extensions 25 37 permits the telescoping or interlocking thereof to be readily carried out during the operation of assembling parts of the structure together. This telescoping or interlocking relation of the extensions 37 with one another thus provides a 30 continuous contacting fin surface across the plurality of spaced apart conduits 11 on each side of the exchanger. This arrangement provides a heat exchanger or condenser structure wherein the temperature gradient between cer- 35 tain portions and relative to other portions thereof is greatly reduced to increase the efficiency of the structure. It is obvious that the fin elements 31 afford a maximum amount of heat transfer fin surface for the exchanger 10 and 40 provide a plurality of narrow air passages through the exchanger to thus cause substantially all air circulated through the exchanger to contact either the fins or the closed fluid conduits there- 45 of or both.

After assembling all of the parts of the exchanger structure 16 in the manner described these plurality of parts may be secured or bonded together in any conventional manner well-known to those skilled in the art and now practiced in the manufacture of such devices. For example, the various assembled parts of the structure 10 may be brazed together with the aid of copper brazing material in a hydrogen furnace by inserting the structure therein or by passing same 55 therethrough. This brazing of the structure will seal the plurality of fluid conduit connections and will provide a metal-to-metal contact of the fin elements 31 with one another and with the conduits 11. The brazing of the structure will also 60 bond the leg portions 35 and 36 of the fin elements 31 to the flat lengthwise extending portion of the plate 17 to thereby provide a unitary heat exchanger of increased structural strength.

Referring now to Figs. 5 and 6 of the drawings 65 it will be noted that I have disclosed a modified closed conduit structure for the heat exchanger 10. In this modified structure a pair of metal strips 41 and 42 having their edges bent over to provide legs are placed together in opposed relation upon a corrugated strip 45. This strip 45 is constructed or formed in a fashion similar to the corrugated strip 22 to provide, when brazed within strips 41 and 42, a closed fluid conduit 70 46. Since the edges 43 and 44 of metal strips 75

41 and 42 are bent or disposed at right angles to the flat longitudinally extending portions thereof a plug or the like element 47 must be placed between the elongated portion 25 of the 5 cap members 12 at the point where the conduit 46 is secured to the cap members. This plug 47 closes the space between the straight sided conduit 46 and the semi-cylindrical inner surface of the portion 25 of cap members 12.

10 From the foregoing it will be seen that I have provided an improved heat exchanger such as a condenser for a refrigerating system and that the improved construction materially increases the efficiency of such devices and provides a device of 15 increased structural strength. By increasing the efficiency of a heat exchanger by incorporating therein the maximum amount of fin surface such structures can be made small and compact and a structure of predetermined size will have greater 20 capacity than heretofore obtainable. The telescoping or interlocking of the separate fin elements with one another in my improved heat exchanger construction provides or forms a continuous contacting fin surface extending entirely 25 across both sides of the exchanger and thereby decreases the temperature gradient between portions of the exchanger. It is thus seen that the increased efficiency of my improved heat exchanger is due partly to the placing of a maximum 30 amount of fin surface extending across the sides of the structure. The improved heat exchanger is simple in construction and the methods of assembling and manufacturing the same can be carried out at low cost.

35 While the form of embodiment of the invention as herein disclosed, constitutes a preferred form, it is to be understood that other forms might be adopted, all coming within the scope of the claims which follow.

What is claimed is as follows:

1. A unitary heat exchanger comprising in combination, a closed fluid conveying conduit having a plurality of spaced apart portions, an element interposed between each of the spaced apart portions of said conduit, each of said elements comprising a single strip of metal bent or folded in zig-zag form to provide a plurality of fins extending between said spaced apart portions of said conduit and disposed in intimate thermal contact therewith, each of said elements being apertured inwardly of an edge portion thereof at the point of said bends or folds to position an end portion of said fins in straddling relation to said conduit portions, and the straddling end portions of said fins of one element being telescoped a substantial distance into the straddling end portions of another of said elements to provide an extended contacting surface between the fins along at least one side of said heat exchanger. 20

2. A heat exchanger including a closed fluid conveying conduit having a pair of elements associated therewith, each of said elements comprising a strip of metal folded back and forth to provide a plurality of fins extending laterally from said conduit and disposed in intimate thermal contact therewith, each of said elements being apertured inwardly of an edge portion thereof at the point of said folds to position an end portion of said fins in straddling relation to said conduit, and the straddling end portions of said fins of one element being telescoped a substantial distance into the straddling end portions of the other of said elements to provide an extended contacting surface between the fins along a side of said 30 conduit. 35

HARRY F. SMITH.
